DESIGN FOR A POWDER CAN CAP

John F. Peters, Leonia, N. J., assignor to American
Can Company, New York, N. Y., a corporation
of New Jersey

Application November 7, 1935, Serial No. 59,433

Term of patent 7 years

To the Commissioner of Patents:

Be it known that I, John F. Peters, a citizen of the United States, residing at 372 Park Avenue, Leonia, county of Bergen, and State of New Jersey, have invented a new, original, and ornamental Design for a Powder Can Cap, of which the following is a specification, reference being had to the accompanying drawing forming a part thereof.

On the drawing:

Figure 1 is a perspective view of a powder can cap showing my new design;

Fig. 2 is a top plan view of the same; and

Fig. 3 is a side elevation of the same.

I claim:

The ornamental design for a powder can cap, as shown.

JOHN F. PETERS.
